FILLER FOR POCKETBOOKS AND THE LIKE

Michael A. Scott, Hollis, N. Y., assignor to Peters Bros. Rubber Company, Inc., Brooklyn, N. Y., a corporation of New York

Application June 24, 1938, Serial No. 215,652

6 Claims. (Cl. 150—28)

The present invention relates to an improvement in reinforcing liners, and is especially applicable to the padded reinforcement of flaps of pocketbooks, hand purses and the like.

5 The important feature herein lies in the combining, by a suitable adhesive, of a more or less flexible paper backing, superposed by an adhered textile facing, the latter in turn having superposed thereon an adhered felted padding, in the 10 present instance and for the purpose outlined, this padding may be of cotton batting of about one eighth of an inch in thickness, more or less.

The main purpose of the present padding is to give flexible thickness to such purse or bag 15 flaps, retaining flexibility of the finished flaps, reinforcing the paper by the textile web and maintaining the cotton batting in its desired location, without creeping and becoming bunched in spots. Thus the flap is kept smooth and 20 flexible, is soft to the touch and has a pleasing fullness.

The foregoing and other features of advantage will be apprehended as the herein description proceeds, and it will be obvious that modifications may be made in the structure herein 25 without departing from the spirit hereof or the scope of the appended claims.

In the drawing,

Fig. 1 is a plan view of the reinforcing padding 30 or liner;

Fig. 2 is a vertical, sectional view taken anywhere across Fig. 1; and

Fig. 3 is an enlarged sectional view of any 35 traversing section of Fig. 1.

The three components of the present padding, as combined, are flexible, and each contributes to the function of forming a flexible shift proof padding within the interior of the purse flap, between the inner flap lining and outer facing 40 thereof which may be of leather or otherwise.

The padding as shown, comprises a semi-flexible paper base forming portion P, upon which is adhered a textile fabric T, which may preferably be of an open weave, such as cheese cloth 45 or the like though other closer woven textiles may be used.

Upon the textile T is adhered a cotton batting facing C of any desired thickness usually about one eighth of an inch in thickness, more or 50 less. The adhesive, whereby the three elements of the padding are combined into a single sheet, may be of any suitable kind, but is thinly applied, so as to leave the assembled padding pliable, but firmly combined or adhered together.

55 The usual purse or bag flap structures, un-

padded, comprises an inner textile lining, such as silk, mohair or the like which is sewn by its margins to an outer covering such as another heavier textile of ornamental nature, or the covering may be of leather or imitations thereof. 5 It is between the flap lining and cover that the present padding is inserted, the paper base of the padding being faced against the flap lining with the cotton facing C faced against the inside face of the outer flap covering. Thus, the cotton 10 facing C, is, in effect a sort of upholstering filling for the flap, and which, to an extent, leaves the padded flap pliable, without tendency to wrinkle, and gives substance to the flap, without undue stiffness.

15 Due to the materials used in the combined padding, it is easily cut to any desired flap contour, thus rendering the padding useful in the many varied ornamental flap designs encountered in the purse or bag flap art.

20 Having thus described the invention what is claimed is:

1. A flap of a purse or similar article including a lining and an outer covering; and a padding inserted therebetween and comprising a 25 batting, a semi-flexible base and a fabric secured between said batting and base at substantially all parts of their adjacent faces in a manner leaving the padding pliable.

2. A flap of a purse or similar article including 30 a lining and an outer covering; and a padding inserted therebetween and comprising a batting facing faced against the covering; a semi-flexible paper base faced against the flap lining, and a fabric between said batting and base; said fabric 35 being secured to the base and batting in a manner leaving the padding pliable.

3. A flap of a purse or similar article including 40 a textile lining and an outer covering; and a padding inserted therebetween and comprising a batting facing faced against the covering; a semi-flexible paper base faced against the flap lining, and a fabric between said batting and base; said fabric being secured to the base and batting at substantially all parts of their adjacent faces in a manner leaving the padding pliable; the base reinforced by the fabric maintaining the batting in its location without creeping; said padding being cut to the flap contour 45 and giving pleasing soft, smooth flexible fullness to the flap and holding the flap against tendency to wrinkle or stiffness.

4. Padding for use in flaps of pocketbooks, purses, bags or the like including a lining and an outer covering of leather or similar material 55

sewn together at margins thereof; said padding comprising a cotton batting facing about one eighth of an inch in thickness adapted to be faced against the covering; a semi-flexible paper base adapted to be faced against the flap lining; and an open work cheese cloth textile fabric between said batting and base; said textile fabric being adhered to the base and batting by a thinly applied adhesive leaving the padding pliable; the paper base reinforced by the fabric maintaining the batting in its location without creeping; said padding being adapted to be cut to the flap contour and giving soft, smooth flexible thickness and pleasing fullness to the flap and retaining the flexibility of the flap; the padding leaving the flap pliable without tendency to wrinkle, and giving substance to the flap without stiffness.

5. A padding reinforcement of the class described comprising, for combination with the flap of a pocketbook, hand purse or the like including a textile flap lining and an outer covering of leather or leather-like or other material sewn together at margins thereof, a padding disposable between the lining and covering and conforming to the contour of the flap and comprising a soft cotton batting about one eighth of an inch in thickness engageable against the covering, a semi-flexible paper base engageable 20 against the flap lining, and an open work cheese cloth textile fabric between said batting and base; said textile fabric being adhered to the base and batting by a thinly applied adhesive leaving the padding pliable; the paper base reinforced by the fabric maintaining the batting in its location without creeping; said padding being cut to the flap contour and serving to give soft, smooth flexible thickness and pleasing fullness to the flap and retain the flexibility of the flap; the padding fitting in the lining and being large enough to hold the flap extended, thus preventing 25 tendency of the flap to wrinkle, and giving substance to the flap without stiffness; the cotton batting being free of less soft materials and having one face free of any base, and adapted to engage directly against the leather to provide a 30 soft non-lumpy backing for the leather; the faces of the padding being unsecured or unadhered to the lining and covering, leaving the lining and covering freely flexible and soft.

35

give substance to the flap without stiffness; the cotton batting being free of less soft materials and having one face free of any base, and adapted to engage directly against the leather to provide a soft non-lumpy backing for the leather. 5

6. A padding reinforcement of the class described comprising, in combination with the flap of a pocketbook, hand purse or the like including a textile flap lining and an outer covering of leather or leather-like or other material sewn 10 together at margins thereof, a padding disposed between the lining and covering and conforming to the contour of the flap and comprising a soft felted cotton batting loosely engaged against the covering, a semi-flexible paper base loosely engaged against the flap lining, and an open work cheesecloth textile fabric between said batting and base; said textile fabric being adhered to all parts of the adjacent faces of the base and batting by a thinly applied flexible adhesive leaving the padding flexible; the paper base being reinforced by the fabric and maintaining the batting in its location adjacent to the edges of the flap, and preventing the batting from creeping or bunching; said padding being cut to the 15 flap contour and serving to give soft, smooth, flexible thickness and pleasing fullness to the flap and retain the flexibility of the flap; the padding fitting in the lining and being large enough to hold the flap extended, thus preventing 20 tendency of the flap to wrinkle, and giving substance to the flap without stiffness; the cotton batting being free of less soft materials and having one face free of any base, and adapted to engage directly against the leather to provide a 25 soft non-lumpy backing for the leather; the faces of the padding being unsecured or unadhered to the lining and covering, leaving the lining and covering freely flexible and soft.
